UNITED STATES PATENT OFFICE.

LYNN ERVINE MARTIN, OF PADUCAH, KENTUCKY.

AUTOMATIC ELEVATOR GATE.

1,426,663.

Specification of Letters Patent. Patented Aug. 22, 1922.

Application filed May 11, 1920. Serial No. 380,655.

To all whom it may concern:

Be it known that I, LYNN ERVINE MARTIN, a citizen of the United States, residing at Paducah, in the county of McCracken 5 and State of Kentucky, have invented a new and useful Automatic Elevator Gate, of which the following is a specification.

The present invention has reference to gates or guards for closing elevator shafts. 10 the primary object being to provide means for rendering the elevator shaft fire-proof and at the same time guard against persons walking into an open shaft.

A further object of the invention is to 15 provide novel means of this character especially designed for use in connection with freight elevators, and one which will be automatic in its operation.

A still further object of the invention is 20 to provide a guard which will operate by its contact with the elevator moving in the shaft, which the elevator closes, thus insuring the opening and closing of the gate or guard, when the elevator is operated by 25 persons unfamiliar with police and fire regulations.

With the foregoing and other objects in view which will appear as the description proceeds, the invention resides in the combination and arrangement of parts and in the details of construction hereinafter described and claimed, it being understood 30 that changes in the precise embodiment of the invention herein disclosed, may be made 35 within the scope of what is claimed, without departing from the spirit of the invention.

Referring to the drawings:—

Figure 1 illustrates a front elevational view of the lower gate;

Figure 2 illustrates a front elevational view of the same, showing the gate partly broken away, to illustrate the connection between the supporting members and the curtain, forming a part of the gate;

Figure 3 illustrates a side elevational view of the upper gate employed for closing the lower door of the shaft;

Figure 4 illustrates a side elevational view of the gate closing the upper door of the 50 shaft;

Figure 5 illustrates a sectional detail view, showing the supporting pipe and curtain; and

Figure 6 illustrates a front elevational view showing the guard as in its closed or folded position.

Referring to the drawings in detail, the reference character 5 designates the front wall of an elevator shaft, which is provided with opposed vertical grooves 6, formed by 60 the vertical guide members 7, which are secured to opposite sides of the wall 5.

The gate proper is indicated by the reference character 8, and includes a flexible body portion formed preferably of asbestos, 65 the length and width of which asbestos is equal to the height and width of the opening to be closed by the gate, so that when the gate is in its extended position, the opening will be entirely closed. 70

Carried by the inner surface of the flexible body portion, are the horizontally disposed bracing elements 9, that are in the form of metallic pipe sections which are secured to the body portion by means of the strap 75 members 10 disposed adjacent to the ends of the bracing elements 9, and as shown these bracing elements 9 are disposed in suitable spaced relation with each other to permit the body portion of the gate to 80 fold between the elements 9.

Carried by the side walls 11 of the elevator shaft, are the track-ways 12, which track-ways accommodate the ends of the operating rod 13 which extends transversely 85 of the shaft and lies within the path of travel of the arm 14 forming an extension of the lower beam 15 of the elevator.

This operating rod has connection with the lower portion of the gate 8, through the 90 medium of the flexible connecting member 16, which operates over the roller 17, carried by the bracket 18 which in turn is supported adjacent the upper edge of the opening of the shaft, and since the upper end of 95 the gate proper has connection with one wall of the elevator shaft as by means of the flexible connection 19, the upper end of the gate proper is maintained in proper relation with the elevated shaft. 100

From the foregoing it is obvious that when the elevator descends, the arms 14 thereof contact with the operating rod 13 to carry the operating rod downwardly to the lower end of the shaft, with the result that 105 the gate proper moves upwardly, portions thereof folding between the elements 9 to open the shaft to permit of access to and from the elevator. Upon movement of the elevator in the opposite direction, the gate 110 proper unfolds to an extended position, due to the weight of the bracing elements 9 fall-

ing by gravity to the limits of their downward movement.

The gate structure which operates to close the upper opening of the shaft, is similar to that described, since the same includes a flexible body portion 8', which supports the bracing elements 9' in spaced relation with each other, the spacing elements 9' having their ends operating in the grooves or trackways 10' formed in the side walls of the opening which the gate closes.

Connecting the adjacent lower bracing elements 9', is a vertical coupling 11' which provides means for connecting the horizontal arms 12' to the gate, and since these arms 12' are carried at opposite ends of the lower elements 9', it is obvious that when the elevator, the top of which is indicated by the reference character 13', contacts with the horizontal arms 12', the gate proper is folded during the movement of the elevator upwardly, with the result that when the elevator has reached the limit of its upward movement, the gate proper is in a folded 25 position.

It follows that when the elevator moves

downwardly, the weight of the bracing elements 9' will cause the gate proper to unfold, and assume an extended, or closed position.

Having thus described the invention, what is claimed as new is:—

In combination with an elevator, vertical guideways supported adjacent to the elevator, a gate embodying a flexible structure, 35 horizontally disposed bracing elements having connection with the gate and having their ends disposed in the guideways, vertically disposed trackways, an operating rod having its ends positioned in the trackways 40 and having connection with the gate, and an arm carried by the elevator and contacting with the rod to move the gate to an open position.

In testimony that I claim the foregoing 45 as my own, I have hereto affixed my signature in the presence of two witnesses.

LYNN ERVINE MARTIN.
